UNITED STATES PATENT OFFICE.

FREDERICK AUGUSTUS ROE, OF LONDON, ENGLAND, ASSIGNOR TO
DONALD W. DICKSON, OF SAME PLACE.

HORSESHOE-MACHINE.

SPECIFICATION forming part of Letters Patent No. 350,603, dated October 12, 1886.

Application filed December 16, 1885. Serial No. 185,815. (No model.) Patented in England July 1, 1885, No. 8,001.

To all whom it may concern:

Be it known that I, FREDERICK AUGUSTUS ROE, gentleman, a citizen of the United States of America, and a resident of London, England, have invented new and useful Improvements in the Manufacture of Horseshoes and in Machinery or Apparatus therefor, (for which I have obtained provisional protection in Great Britain, No. 8,001, bearing date July 1, 1885,) of which the following is a specification, reference being had to the accompanying drawings.

My invention relates to the manufacture of horseshoes and to machinery or apparatus therefor, and comprises various improvements hereinafter described.

In the specification of former Letters Patent, dated October 10, 1882, No. 265,705, the manufacture of spring-horseshoes by means of specially-designed machinery or apparatus is described. This apparatus comprises a pair of curved dies for drawing the blanks and forming the calks thereon, and another pair of dies for finishing the blanks; but by these dies only one-half of the blank is operated upon at a time—that is to say, after one half of the blank has been shaped or finished by either pair of the said dies, the blank must be reheated and the other half thereof inserted between the dies, in order that the two halves of the blank shall be shaped as required for the two sides of the shoe.

One object of my present invention is to provide for the manufacture of horseshoes by one operation of each pair of dies employed.

In the accompanying drawings, Figure 1 is a plan view of a bending-machine, showing the parts in the positions which they occupy when the machine is ready for starting. Fig. 2 is a plan view of the same with the parts in different positions. Fig. 3 is a vertical longitudinal central section showing the parts in the position which they occupy when the operation of bending the blank is completed. Fig. 4 is an enlarged transverse sectional view on the line $x-x$ of Fig. 2. Figs. 5, 6, 7, and 8 are details to be referred to.

In Figs. 1, 2, 3, and 4, d is the base-plate of the machine. e is a former, which is designed to operate in combination with dies, herein-after described, to bend the blanks to the de-

sired shape, and which is firmly attached, by bolts e' or otherwise, to the flattened end of a bar or rod, e^2 . This bar is secured, by bolts or otherwise, to a block, e^3 , fitted to slide to and fro between guides d' d^2 , fixed or formed on the base-plate d . The said block is coupled by means of a connecting-rod, f , to the pin g' of a disk-crank, g , which is fixed upon a shaft, h , carried in bearings h' , and which acts as a fly-wheel. A toothed wheel, h^2 , is mounted loosely upon the shaft h , and is adapted to be connected therewith or disconnected therefrom by means of a clutch, h^3 , operated by a foot-lever or treadle, i , through the medium of the levers i' i^2 .

j is a pinion, which is fixed on a shaft, j' , carried in bearings j^2 , and which is geared with the wheel h^2 .

j^2 is a driving-pulley fixed on the shaft j' , which pulley is to be connected by a belt with any suitable-motor. By these means reciprocating motion is imparted to the former e , for the purpose hereinafter specified.

k k' are dies whose inner edges have the shape or configuration which it is desired to give to the shoe. These dies are firmly secured, by bolts or otherwise, to blocks or holders k^2 , pivoted at k^3 to a plate, l , resting upon the base-plate d , so that it is free to slide thereon.

k^4 is a tie-bar connecting the pivots of the holders k^2 .

m m' are two links, which fit into vertical grooves or recesses in the holders k^2 and in blocks n , so that they will act like a toggle-joint. The blocks n have screw-threaded extensions n' , which are passed through lugs or brackets d' , formed on or secured to the base-plate d , and are provided with nuts n^2 . Washers or distance pieces n^3 are placed upon the extensions n' between the blocks n and the lugs d' . By slackening the nuts n^2 , removing the washers n^3 , and inserting washers of greater or less thickness in place thereof, the dies k k' and holders k^2 can be adjusted to suit different sizes of shoes. The links m m' are coupled to the holders k^2 and blocks n by bars or links m^2 .

o o are adjustable blocks provided with anti-friction rollers o' , and so arranged that the former e in its to-and-fro movement will pass between them. These blocks have screw-threaded extensions o^2 , which are passed

through lugs or brackets d^4 , formed on or secured to the base-plate d , and are provided with nuts o^3 . Washers or distance pieces o^4 are placed upon the extensions o^2 , which washers can be replaced by thinner or thicker washers, as above described with reference to the blocks n . The said blocks o are formed with slots o^5 , and are secured to the base-plate d by bolts o^6 , passing through the said slots.

10 $p p$ are springs attached to the blocks o , for the purposes hereinafter specified.

15 l' is a weight attached to one end of a rope or chain, l' , which passes around a pulley, l^3 , carried by a bracket, d^5 , formed on the base-plate d . The other end of the said rope or chain is attached to a rod, l^4 , passing through a guide-block, d^6 , secured to the said base-plate. This rod is attached, by a bolt, l^5 , or otherwise, to the plate l .

20 The operation of the machine is as follows—that is to say: In Fig. 3 the parts are, as above stated, shown in the positions which they occupy when the machine is ready for starting. The blank B is placed endwise between the 25 springs p , as shown, which springs hold the said blank until the former e acts thereon, as hereinafter described. The said springs permit of readily ascertaining whether the blanks are of the proper length to form a shoe of the 30 desired size, because if a blank is too long it cannot be inserted between the said springs, while if a blank is too short it will not touch the two springs. After a blank of the proper length has been heated and inserted between 35 the said springs, as shown, the treadle i is depressed to start the machine. The rotation of the disk-crank g first causes the former e to move forward or toward the dies $k k'$. In this forward movement a pointed stud or projection, e^4 , on the former e first enters the blank 40 at the center thereof, and thus prevents its displacement while being bent. The said former then forces the blank between the rollers o' , and thereby bends the said blank. It then 45 thrusts the said blank between the dies $k k'$, thereby moving the said dies and the plate l forward, this movement being assisted by the weight l' . The dies $k k'$ in their forward movement are turned around or about their pivots 50 by the links $m m'$, and the blank is thus forcibly pressed between the dies $k k'$ and the former e , to impart to it the required shape. The parts then occupy the positions indicated in 55 Fig. 2, in which S indicates the shoe. While the blank is being bent the flattened head of the bar e^2 holds down the shoe and prevents the twisting or distortion thereof. The continued rotation of the wheel g causes the backward or return movement of the former e . In 60 the first part of this backward movement the plate l and dies $k k'$ move back with the former e , so that the said dies are opened by the links $m m'$. In the continued backward movement of the former e the shoe is withdrawn thereby 65 from the dies $k k'$ and moved back with the said former until it arrives over the aperture

d^7 in the base-plate d , through which aperture it will fall upon the ground or into a suitable receptacle.

The former e and forming-dies $k k'$ are removable from the rod e^2 and the holders k^2 , and can be replaced by other formers and dies. Therefore the machine can be adapted for manufacturing horseshoes differing in size or in shape, or in both size and shape. The manner in which the dies $k k'$ are secured to their holders is more clearly shown in Fig. 5.

In Figs. 6 to 8, inclusive, I have shown a pair of drop-dies, $A B$, the lower one, A , of which is made with a groove or channel, A' , 80 and the upper one, B , of which is made with a projection, B' , which will fit into the groove or channel A' . The said projection, however, leaves a space at the inner end of the groove or channel A' , so that when a shoe is compressed between the said dies the metal will be forced into the said space, and a toe-clip 85 will thus be formed on the shoe.

I provide the means, hereinafter described, whereby the shoe can be readily removed from 90 the lower die after it has been operated upon therein—that is to say, a forked lever, C , is pivoted at C' to the lower die, A , and is coupled to two rods, D , which extend through holes in the said die, so that they will bear 95 against the under side of a shoe therein. This lever is arranged to be operated either by hand or by the foot, or automatically by the same means whereby the upper die is raised, or by 100 any other suitable means.

I do not claim in this application the rolls between which the billet is passed to form the blanks, nor do I claim the cutters herein shown and described, as these features are designed to form the subject-matter of application to be filed hereafter.

What I claim is—

1. The combination, with the base-plate having lugs or brackets d^4 , of the former e and mechanism for imparting reciprocating motion thereto, the adjustable blocks o , having threaded extensions, the rollers mounted in said blocks, the adjusting-washers on the threaded extensions, and the pivoted dies $k k'$, substantially as herein described.

2. The combination, with a suitable base-plate, of the pivoted dies $k k'$, the adjustable blocks $n o$, the adjusting-washers, a link-connection between the base-plate and the blocks n , and the former e and operative mechanism, substantially as herein described.

3. The combination, with the former e and means for imparting reciprocating motion thereto, of the dies $k k'$, the holders k^2 , pivoted to the sliding plate l , the links $m m'$, and the adjustable blocks n , substantially as and for the purpose set forth.

4. The combination, with the sliding plate carrying the dies $k k'$ and the pivoted holders k^2 , of the weight l' , attached to the said plate 130 by a cord or chain passing over a pulley, substantially as and for the purpose set forth.

5. The combination of the drop-dies formed with the groove or recess A' and the projection B', substantially as and for the purpose set forth.
- 5 6. The drop-die A, having a groove or recess, A', and the die B, having a projection, B', in combination with a forked lever, C, and the rods D, substantially as herein described.

In testimony whereof I have hereunto signed my name in the presence of two subscribing to witnesses.

FREDERICK AUGUSTUS ROE.
